(57) CLAIM

The ornamental design for a display screen with animated graphical user interface, as shown and described.

DESCRIPTION

FIG. 1 is a front view of a first image in the sequence for a display screen with animated graphical user interface, showing our new design;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof; and,

FIG. 8 is a front view of an eighth image thereof.

The broken lines of the display screen, and various features of the graphical user interface, are included for the purpose of illustrating environmental structure and portions of the article, and form no part of the claimed design. The areas shown below/underneath/through the stippling form no part of the claimed design.

The dash-dot-dash lines illustrate unclaimed boundary lines and form no part of the claimed design. Stippled areas inside the dash-dot-dash lines are the only subject matter that is claimed.

The appearance of the image transitions between images shown in FIG. 1 through FIG. 8. The process or period in which one image transitions to another image forms no part of the claimed design.
